DIE POLISHING OR LAPPING MACHINE

Norman Samuel Hardy, Rugby, England, assignor
to Kneller (Instruments & Tools) Limited,
Rugby, England

Application April 8, 1949, Serial No. 86,129
In Great Britain April 16, 1948

9-Claims. (Cl. 51—62)

1

This invention concerns die polishing (which expression includes lapping) machines of the type comprising a pair of spaced wire holders for holding a taut wire between them, a rotary work head for the reception of the die with the wire extending through its aperture, and means for effecting relative reciprocation between the wire holders and the work head so that the wire is caused to rub to and fro through the die as the latter is rotated. Such machines commonly used for polishing the dies (made of diamond or other hard material such as tungsten carbide) employed for wire drawing and an object of the present invention is to effect improvements on these machines.

It will be understood that as the relative reciprocations take place the die rubs on a certain length of the wire which for the sake of convenience is referred to herein as the rubbing zone. It is undesirable that this rubbing action should always take place on the same length of wire and therefore the present invention provides a die polishing machine of the type specified having automatic means for effecting a progressive and gradual adjustment first in one direction and then in the reverse direction between the wire holders and the work head in such manner that the rubbing zone is gradually shifted along the wire first in one direction and then in the reverse direction. For this purpose the machine preferably comprises a frame on which the two wire holders are mounted, a reciprocating driver, a driving connection between the driver and the frame, and means for gradually increasing and decreasing the effective length of the driving connection. It will thus be appreciated that without any alteration in the stroke of the frame the mean position of the latter in relation to the head is gradually adjusted, thereby producing a corresponding displacement of the rubbing zone.

The automatic means before mentioned may comprise an adjusting screw mechanism, forward and reverse racking means for it, and change-over means for changing the direction of the racking movement. In particular there may be an adjusting screw, racking mechanism for racking it in either direction, and change-over means for determining the direction in which it is racked. This adjusting screw may form the driving connection aforesaid.

The invention also provides a die polishing machine of the type specified, having means for effecting relative adjustment between the wire and the work head in two mutually transverse directions each substantially normal to the

length of the wire. This permits adjustment to be made in one direction according to the required external diameter of the die and adjustment to be made in a transverse direction according to the diameter of the wire. Preferably the wire is (e. g. the wire holders are) adjustable in one direction and the head is adjustable in a transverse direction.

The invention further provides a die polishing machine of the type specified, having a standard or body carrying on each side of it a pair of wire holders and the associated work head, and having mechanism for effecting reciprocation between each pair of wire holders and the associated head. This mechanism may be common to both parts of the machine. The advantage of this construction is that the machine may be built more cheaply and occupies less space than two single machines while furthermore it results in the various parts requiring adjustment being accessibly located.

The foregoing and other features of the invention set out in the appended claims are incorporated in the die polishing machine of the type specified which will now be described as an example with reference to the accompanying drawings in which

Figures 1 and 2 are perspective views of the machine, looking from the front and rear respectively;

Figure 3 is a cross section, taken in a vertical plane, showing the frame, the mechanism for reciprocating it, and the mechanism for effecting the progressive adjustment before mentioned;

Figure 4 is a cross section, taken in a vertical plane, through one of the work heads;

Figure 5 is a sectional elevation and Figure 6 is a plan of a portion of the mechanism for effecting the said progressive adjustment.

This machine is a double machine, comprising a standard or body 1 carrying at each side of it a work head 2a, 2b respectively and being equipped with a single vertically reciprocatable frame 3 carrying two pairs (viz. 4a, 5a, and 4b, 5b) of wire holders, each arranged to co-operate with one of the heads. The frame 3 comprises a member 6 slidably mounted in the vertical guides 10 on the standard 1 and provided at the top and bottom with cross bars 7 and 8 respectively. Each arm of each cross bar carries a wire holder that is capable of being adjusted along the length of the arm, viz. in a direction normal to the length of the wire, the latter being vertical. Alternatively each wire holder is so constructed as to permit the wire to be shifted along the length of

the arm without the holder itself being shifted. A scale 9 is provided for the aforesaid adjustment of each wire.

The two work heads 2a, 2b are substantially identical and it is therefore only necessary to describe the work head 2a in detail, with particular reference to Fig. 4, it being pointed out that like parts in, or associated with, the two heads 2a, 2b have like reference numbers distinguished as regards the head 2a by the addition of reference a and as regards head 2b by the addition of reference b.

The head 2a comprises a chuck 10a in which the die to be lapped or polished may be mounted and this chuck is itself rotatably mounted in a casing or body 11a and driven through belts 12a and 14 or other gearing from a driving motor 13 and a lay shaft 15. The head casing 11a is carried by a bracket 16a which is mounted on horizontal guides 17a formed on the associated side face of the standard 1 and extending from front to rear. The bracket 16a together with its head 2a is therefore adjustable horizontally along the guides 17a in a direction which is normal to the length of the wire and is transverse to the direction in which the wire is adjustable. Means 18a are provided for locking the bracket in the desired position of adjustment.

It is desirable that the machine should incorporate facilities for lapping dies having a conical aperture or having an aperture provided with a conical counter-sink, and dies having one edge of the aperture formed with a radius. For the first purpose means are provided whereby each head may be so adjusted that its axis of rotation is inclined to the vertical, and for the second purpose each head is provided with means whereby as the head is rotated its axis of rotation may be repeatedly and slowly rocked into and out of the vertical.

These features are exemplified in head 2a. Its mounting bracket 16a incorporates a horizontal spindle 19a to the front end of which the head is attached. The attitude of the axis of the head may be set either by adjusting the head on the end of the spindle 19a or by adjusting the spindle rotationally within the bracket 16a. Conveniently there is a lug 20a protruding upwards from the head casing 11a and provided with a slot 22a which is transfixied by the end of the spindle, the lug being gripped between a collar 23a on the spindle and a nut 24a on the end of the latter. It will be understood that if the head is set so that its axis is inclined to the vertical, the machine is thereby adapted to polish or lap a conical diehole or one having a conical counter-sink. The lug 20a is provided with an adjusting screw 25a extending into the slot 22a to bear against the spindle 19a, so that the height of the head may readily be adjusted. Attention is also directed to the clamping screw 21a in bracket 16a, which permits the spindle 19a to be clamped in any desired rotational position. Thereby the head 2a may be fixed with its axis at any desired angle to the wire, and/or (in conjunction with the adjustment afforded by slot 22a, adjusting screw 25a, and clamping nut 24a) permits the head to be adjusted laterally of the wire (with its axis either parallel with or disposed at an angle to the wire) and clamped in the adjusted position.

In order that a radius at one end of the die-hole may be polished or lapped the rear end of each spindle 19a, 19b is provided with a crank arm 26a or 26b which is connected by a connecting rod 27a or 27b to one arm of a rock lever 28a

or 28b which is pivoted intermediate its ends (at 29a or 29b) and carries on the other arm a cam follower 30a or 30b engaging a rotatable cam 31 which is driven through suitable gearing (see 32 Figs. 1 and 2, and 33, Fig. 3) from the driving motor 13 of the machine. The cam followers 30a, 30b for the two heads engage the same cam 31 at substantially diametrical opposed locations under the influence of spring 34 and it will be appreciated that the arrangement is such that as the cam 31 rotates the rock levers 28a, 28b are rocked and if the locations at which the connecting rods 27a, 27b are pivoted to them are offset from the axes about which the levers rock then the two spindles 19a, 19b are rocked to and fro and the two heads 2a, 2b are rocked so that their axes of rotation are slowly moved to and from the vertical.

Means are provided for adjusting the points, at which the connecting rods 27a, 27b are pivoted to the rock levers 28a, 28b, into and out of coincidence with the axes of said levers thus permitting the angle through which each head is rocked to be adjusted, it being understood that when the said points are coincident with the axes of the levers the heads are not rocked at all. For example each rock lever may comprise a bar which transfixes a block 34a or 34b to which the connecting rod 27a or 27b is pivoted, the said block being adjustable along the bar and being clamped in its position or adjustment by a clamping screw 35a or 35b.

The effective length of each connecting rod 27a, 27b is also adjustable, for which purpose the lower end of the rod may slidably transfix a socket 36a or 36b pivoted to the end of the associated crank arm 26a or 26b, the socket being provided with a screw 37a or 37b for clamping the rod in the desired position of adjustment.

The frame 3 carrying the wire holders is reciprocated vertically by the following mechanism. The standard 1 carries a vertically slidable plunger 39 (Fig. 3) the top end of which is provided with a forwardly protruding arm 40 in which a vertical lead screw 41 is rotatably mounted, the lower end of this lead screw screwing through a nut 42 carried by the frame. The lower end of the plunger 39 is attached to a cross piece 43 having a horizontal cylindrical bore in which a cylindrical slider 44 is mounted, and this slider 44 is pierced with cross bore 45 into which a crank pin 46 protrudes through a slot 47 extending lengthwise of the cross member 43. The crank pin 46 is mounted on a crank shaft 48 (advantageously carrying the cam 31) which is driven from the driving motor 13 through reduction gearing 33 and it will therefore be understood that as the crank pin 46 travels in its circular path the slider 44 travels with it and also slides to and fro inside the cross member 43 with the result that the plunger 39 is raised and lowered and the frame 3 is reciprocated.

This reciprocation of the frame causes the wires to be reciprocated vertically so that they rub on the internal peripheries of the dies carried by the rotating work heads 2a, 2b. In order to adjust the rubbing zones the lead screw 41 is racked round first in one direction through a predetermined number of motions and then in the reverse direction. Thereby the rubbing zones are gradually shifted first towards one end of the wires and then towards the other end thereof. The step-by-step rotation of the screw in effect adjusts the length of the connection that extends between the frame 3 and the reciprocating arm

40 which drives it. It is produced by the following mechanism.

The top end of the screw 41 carries a ratchet wheel 49 with square teeth 50 on its upper surface. On the top of the standard there is pivoted at 54 a pendulous member 51 which carries two pivoted pawls 52, 53 that extend, from their pivots, inwards towards one another and are both capable of engaging the ratchet wheel 49. The pendulous member 51 is movable between right and left hand positions which are determined by stops 55, 56, a spring detent 57 being provided for maintaining it in either position. When in the right hand position the left hand pawl 53 is operative and the right hand pawl 52 inoperative and when in the left hand position (Figs. 5 and 6) the right hand pawl 52 is operative and left hand pawl 53 inoperative. The pawls 52, 53 change over as the pendulous member 51 moves from one position to another.

For holding either pawl inoperative there is a bluff 58 freely mounted on the top end of screw 41 above the ratchet wheel 49. This bluff has a cut out 59 of sufficient size to permit one pawl only to engage the teeth 50 and is provided with stop pins 60, 61 between which a pin 62 on the pendulous member 51 is received. Thus, when the pendulous member 51 swings to the left (Figs. 1 and 6) to bring the right hand pawl 52 into operation, the bluff 58 is moved in a clockwise direction, Fig. 6, to bring the cut out 59 under pawl 52 and to bring a plane part under pawl 53 so that the latter is prevented from engaging the teeth 50.

As the frame 3 rises the ratchet wheel 49 is brought into engagement with the operative pawl and the latter is swung up about its pivot 63 and 64. The arc of movement of the end of the pawl is such that in this swinging movement the ratchet wheel 49 is rotated through one tooth space. The pressure of the pawl tends to swing the pendulous member 51 away from the extreme position then occupied by it. This tendency is normally overcome by the spring detent 57 but, when the screw 41 has been adjusted to a predetermined extent in either direction, limit stop mechanism prevents its further rotation in that direction. Since the ratchet wheel 49 is thus prevented from further rotation the forces acting on the operative pawl now become sufficiently large to overcome the restraining influence of the detent 57. The pendulous member 51 is therefore forced over to the other extreme position and in this movement the bluff 58 is shifted so that the previously operative pawl is lifted to its inoperative position and the other pawl is lowered to its operative position. This other pawl thereupon proceeds to rack the screw in the reverse direction each time the frame reaches the top of its stroke.

The limit stop mechanism may consist of upper and lower stop pins 65, 66 protruding from the frame 3 and a plate or other member 67 fixed on the screw 41 and having two diametrically-opposed tongues 68, 69 one of which is directed upwards and the other downwards. When rotation of the screw 41 carries the nut 42 and frame 3 downwards, the upturned tongue 68 eventually fouls the top stop pin 65 and prevents further rotation of the screw; upon rotation of the screw in the reverse direction the downturned tongue 69 eventually fouls the lower pin 66 and prevents further rotation in said reverse direction.

I claim:

1. A die polishing machine of the type com-

prising a pair of spaced wire holders for holding a taut wire between them, a rotary work head for the reception of the die with the wire extending through its aperture, and means for effecting relative reciprocation between the wire holders and the work head so that a rubbing zone of the wire is caused to rub to and fro through the die as the latter is rotated, automatic means mounted on the machine and acting while the machine is in operation for effecting a progressive and gradual adjustment first in one direction and then in the reverse direction between the wire holders and the work head and for thereby gradually shifting the rubbing zone along the wire first in one direction and then in the reverse direction.

2. A machine according to claim 1, wherein the automatic means comprises an adjusting screw mechanism, forward and reverse racking means therefor, and change-over means for changing the direction of the racking movement after a predetermined number of racks in either direction.

3. A machine according to claim 1, comprising 25 a frame on which the two wire holders are mounted, a machine body having guide means on which the frame is reciprocably mounted, a reciprocating driver, guide means on the machine body in which means the driver is reciprocably mounted, an adjustable driving connection extending between the driver and the frame, and means for gradually changing the effective length of the driving connection, first in an increasing and then in a decreasing direction upon a predetermined cumulative change in effective length, and for thereby gradually shifting the frame to and fro in relation to the driver.

4. A machine according to claim 3, wherein the automatic adjusting means comprises an adjusting screw forming the driving connection between the driver and the frame, forward and reverse racking means therefor, and change-over means for changing the direction of the racking movement after a predetermined number of racks in either direction.

5. A die polishing machine, comprising a standard, a frame mounted thereon for reciprocation, two pairs of spaced wire holders on the frame each pair for holding a taut wire extending between the two holders in the direction of reciprocation, two rotary work heads intermediate the wire holders, one for each wire, each adapted for the reception of an apertured die with the wire extending through the die aperture, means for mounting each work head on the standard for adjustment in a direction normal to the direction of reciprocation, means for rotating each die in its work head, means mounting each work head for pivotal movement about an axis substantially normal to the axis of rotation of its die and to the length of the associated wire, means for oscillating the two heads continuously about their axes of pivotal movement, means for adjusting the angular amplitude of such oscillation, means for reciprocating the frame on the standard and for thereby causing a rubbing zone of each wire to rub to and fro through its die as the latter is rotated, and automatic means for effecting a progressive adjustment of the reciprocating frame along the line of its reciprocation on the standard, first in one direction and then in the reverse direction, and for thereby correspondingly progressively shifting the rubbing zones along the wires.

6. In a die polishing machine of the type com-

prising a standard, a frame reciprocatably mounted thereon, a work head on the standard for carrying a rotating die, means for rotating the die, a pair of spaced wire holders on the frame for holding between them a taut wire extending through a hole in the die, and means for reciprocating the frame on the standard so that a rubbing zone on the wire rubs to and fro through the rotating die, the combination of a driver for the frame, means mounting the driver on the standard, lead screw mechanism, connecting the driver to the frame, for reciprocating the latter, and for adjusting the rubbing zone along the wire, forward and reverse racking mechanism for racking the lead screw mechanism and for thereby adjusting said zone, and means for changing over the direction of racking upon a predetermined extent of adjustment in either direction being achieved while the machine is in operation.

7. A machine according to claim 6, wherein the last said means comprises limit stop mechanism.

8. A machine according to claim 6, comprising a ratchet wheel on the frame and connected to the screw mechanism to rack the latter, a pawl carrier on the standard movable between forward and reverse racking positions, a forward racking pawl and a reverse racking pawl mounted on the pawl carrier for engagement, when operative, by the ratchet wheel at each reciprocation of the frame and for thereby racking the wheel and by reaction urging the pawl carrier to change over between its two positions, a bluff movable between a position in which it bluffs the forward pawl and a position in which it bluffs the reverse pawl, a connection between the pawl carrier and the bluff for causing the latter to change over between its two positions when the pawl carrier changes over, limit stop mechanism for preventing rotation of the lead screw mechanism in one direction upon a predetermined rotation in that direction having been achieved and in the opposite direction upon a predetermined rotation in said opposite direction having been achieved, and

5 a spring-loaded detent normally preventing change-over of the pawl carrier but yieldable under the pawl reaction upon rotation of the lead screw mechanism being stopped by the limit stop mechanism.

9. In a die polishing machine of the type comprising a standard, a frame reciprocatably mounted therein, a work head on the standard for carrying a rotating die, means for rotating the die, a pair of spaced wire holders on the frame for holding between them a taut wire extending through a hole in the die, and means for reciprocating the frame on the standard so that a rubbing zone on the wire rubs to and fro through the rotating die, the combination of a driver for the frame, means mounting the driver on the standard, operating connections between the driver and the frame, automatic means for adjusting said connections to gradually shift the frame in relation to the driver, first in one direction and then in the opposite direction, and for thereby gradually shifting the rubbing zone to and fro along the wire, means mounting the work head on the standard for pivotal movement about 10 an axis normal to the length of the wire and incorporating releasable means for securing the work head at any required pivotal angle, and mechanism for oscillating the work head about 15 said axis concurrently with rotation of the die in the head, which mechanism includes adjustable 20 means for pre-setting the angle of oscillation.

NORMAN SAMUEL HARDY.
